UNITED STATES PATENT OFFICE.

WILLIAM D. GARRARD, OF BEDIAS, TEXAS, ASSIGNOR OF TWO-NINTHS TO
JOHN L. CORNER, TWO-NINTHS TO HARVEY A. McDONALD, AND TWO-
NINTHS TO JOSEPH J. PLASTER, OF BEDIAS, TEXAS.

WRENCH.

No. 815,156.

Specification of Letters Patent. Patented March 13, 1906.

Application filed September 20, 1905. Serial No. 279,324.

To all whom it may concern:

Be it known that I, WILLIAM D. GARRARD, a citizen of the United States, residing at Bedias, in the county of Grimes and State of Texas, have invented a new and useful 5 Wrench, of which the following is a specification.

This invention relates to wrenches, and has for an object to provide a wrench embodying new and improved features of 10 convenience, durability, utility, and efficiency.

A further object of the invention is to provide a wrench having a sliding jaw and a handle pivoted to the shank in such a manner 15 that a movement of the handle about the work causes it to move angularly about the pivot and to clamp the sliding jaw upon the work and a detent to prevent a return movement of the jaw.

20 With these and other objects in view the present invention consists in the combination and arrangement of parts, as will be herein-after fully described, shown in the accompanying drawings, and particularly pointed out in 25 the appended claims, it being understood that changes in the form, proportion, size, and minor details may be made without departing from the spirit or sacrificing any of the advantages of this invention.

30 In the drawings, Figure 1 is a perspective view of the improved wrench. Fig. 2 is a transverse sectional view through the sliding jaw and on line 2 2 of Fig. 1.

Like character of reference indicate corresponding parts in both figures of the drawings.

35 In its preferred embodiment the improved wrench forming the subject-matter of this application comprises a shank 10, having at 40 one end a rigid jaw 11, which may be formed integral with the shank, or the two may be connected in any approved manner, as by a mortise 12, in which the end of the shank is inserted and secured by a rivet 13. At the 45 end opposite the jaw the handle 14 is pivoted to the shank, as by the pin 15, through the spaced ears 16, between which is disposed the shank. The shank 10 is provided along one side with the rack 17, having teeth with 50 one side substantially perpendicular and the other side inclined to the shank and with the inclined sides disposed toward the handle. Upon the shank is mounted the sliding jaw

18, having a detent 19, mounted therein and with one or more springs 20 arranged to hold 55 the detent in engagement with the rack 17.

Rigidly connected or integral with the jaw 18 is a thrust-bar 21, the end of which opposite the jaw is pivoted, as by the pin 22, between the spaced ears 23 rigid with the handle. 60

The jaws 11 and 18 may be provided with any approved form of work-engaging faces, as the plane opposing faces 24 and the pipe-engaging faces 25.

It will be readily understood that a movement of the handle, as indicated by the arrow, will move the jaw 18 toward the jaw 11, the detent 19 riding over the inclined sides of the teeth of rack 17 in that direction, but engaging the perpendicular sides to prevent 70 a return movement until the detent is released.

By this construction the movement of the wrench to turn the work will cause the movable jaw to exert a gripping force; but the work may be turned in the reverse direction, 75 as occasion may require, as the detent prevents the separation of the jaws.

It will be obvious that the several parts of the handle may be formed integral or rigidly connected in any approved manner and 80 composed of any approved material or combination of materials and that the same is true in relation to the shank and jaw 11 and the jaw 18 and its thrust-bar 21.

Having thus described the invention, what 85 is claimed is—

1. In a wrench, a shank provided with a jaw rigid therewith, a jaw slidable upon the shank, a handle pivoted to the shank, means connecting the handle and the slidable jaw 90 whereby an angular movement of the handle slides the jaw and means carried by the jaw to prevent a return movement.

2. In a wrench, a shank provided with a jaw rigid therewith and with a rack formed 95 rigidly along one side, a jaw slidable upon the shank, a handle pivoted to the shank, means connecting the handle and the slidable jaw whereby an angular movement of the handle slides the jaw and means carried by 100 the jaw to engage the rack.

3. In a wrench a shank provided with a jaw rigid therewith and with a rack formed rigidly along one side, a jaw slidable upon the shank, a handle pivoted to the shank at 105 the end opposite the jaw, means connecting

the handle and the slidable jaw whereby an angular movement of the handle slides the jaw and means carried by the jaw to engage the rack.

- 5 4. A wrench comprising a shank provided with a jaw rigid therewith and with a rack along one side, a jaw slidable upon the shank a handle pivoted to the shank at the end opposite the jaw, a thrust-bar carried by the 10 slidable jaw and pivoted to the handle and means carried by the jaw to engage the rack.
5. A wrench comprising, a shank provided with a jaw rigid therewith and with a rack

along one side a jaw slidable upon the shank, a handle pivoted to the shank at the end opposite the rigid jaw, a thrust-bar carried by the slidable jaw and pivoted to the handle and a spring-actuated detent carried by the jaw in contact with the rack.

In testimony that I claim the foregoing as 20 my own I have hereto affixed my signature in the presence of two witnesses.

WILLIAM D. GARRARD.
